UNITED STATES PATENT OFFICE.

KENNETH K. McLEOD, OF ST. PAUL, MINNESOTA.

SUCTION MILKING-MACHINE.

1,190,566.

Specification of Letters Patent. Patented July 11, 1916.

Application filed August 20, 1915. Serial No. 46,414.

To all whom it may concern:

Be it known that I, KENNETH K. McLEOD, a citizen of the United States, residing at St. Paul, in the county of Ramsey and State 5 of Minnesota, have invented certain new and useful Improvements in Suction Milking-Machines, of which the following is a specification.

My invention relates to suction milking 10 machines of the type where the pumping members are moved from one set of cows to another, and has for its object to provide such a milking machine wherein the pumping members, valves and suction members 15 are assembled as a single unit, and wherein the power transmission member is of such a flexible nature as to be readily adapted to any combinations of stanchions in a barn.

It is an especial object of my invention to 20 provide means for drawing the milk directly into the pumping cylinders through tubes embodying check and release valve mechanism and releasing the milk successively from said cylinders by means of a double-flap valve having its parts yieldingly connected and operating in unison alternately to open and close the bottom of each pumping cylinder.

In my machine the assemblage is so well 30 unified that the pumping member is readily placed in communication with the power member, and that an ordinary pail or milk-can may be employed, the whole being readily moved from one cow to another.

The full objects and advantages of my invention will appear in connection with the detailed description thereof and are particularly pointed out in the claims.

In the drawings, illustrating the application 40 of my invention in one form, Figure 1 is a plan view of a portion of a barn with a double row of stanchions, showing the arrangement of the power transmission member of my invention and the attachment of the pumping member to the power member 45 at one of the pumping stations. Fig. 2 is an end elevational view of some of the parts shown in Fig. 1. Fig. 3 is a fragmentary side elevational view of some of the parts 50 shown in Figs. 1 and 2. Fig. 4 is a side elevational central sectional view of the pumping member and a portion of the power transmission member. Fig. 5 is a longitudinal sectional view of the parts shown in Fig. 55 4 taken through the central axis of one of the pumping cylinders. Figs. 6 and 7 are

side sectional elevational and rear elevational views, respectively, of one of the arms of the rocker element of my power transmission member and of a portion of the pump rods showing the manner of attaching and locking the pump rods to the rocker arms. Fig. 8 is a side elevational view of my power jack shown in Fig. 2 drawn to a larger scale. Fig. 9 is a view similar to Fig. 8 showing a modified form of applying said jack.

My milking system is shown in Figs. 1, 2 and 3 installed in a barn 10 having a double row of stanchions 11 and 12 and consists of two distinct parts, a milking member 13 and a power transmission member involving a cable 14 which operates as follows. The cable 14 passes over and around a number of pulleys or sheaves 15 located in the barn 75 and attached to the walls of said barn so as to cause said cable to issue from a jack 16 and pass in and about the barn in the vicinity of the stanchions of the cattle or any other convenient place and return again to 80 said jack 16, as clearly shown in Figs. 1, 2 and 3. At each of the milking stations is secured to cable 14 a pair of keeper lugs 17 which engage with sides 18 and 19 of the vertical arm 20 of a rocker member 21, also 85 situated at every station, as best seen in Figs. 4 and 5. The rocker member 21 comprises two oppositely-extending horizontal arms 22 and 23 as well as the aforementioned arm 20, and is pivoted to oscillate on a casting 24 which is stiffened by a brace 25. Casting 24 and brace 25 are both secured to an upright or post 26 purposely erected for their support, or they may be secured to any other available means. The arm 20 of 90 rocker member 21 is provided with a slot 27 through which the cable 14 passes, said slot allowing cable 14 to travel forth and back in a straight line, giving oscillation to rocker member 21 by means of the keeper 100 lugs 17.

The power used to operate my system may be taken from any suitable source, as an engine 28, and is transmitted by a belt 29 or other means to the jack 16 previously referred to. The frame of jack 16, as seen in Figs. 2, 3 and 8, comprises a pair of standards 30 and 31 attached to a base 32. Two shafts 33 and 34 are journaled in the uprights 30 and 31 and are provided with gears 35 and 36 secured thereto and meshing with each other. Shaft 34 is further provided

with a pulley 37 to which the power is given. Shaft 33 is provided with crank arms 38 and 39 extending in opposite directions and secured to opposite ends of said shaft 33. A pair of turnbuckles 40 and 41, or other suitable tighteners, link the ends 42 and 43 of cable 14 with the crank arms 39 and 38. It hence becomes obvious that cable 14 may always be kept tight and that when a proper gear ratio is chosen it will be given reciprocating motion of a rapidity equal to that with which the milking strokes are taken when a cow is milked by hand. A modification of the method of giving reciprocating motion to the cable 14 is shown in Fig. 9, where the cranks 38 and 39 of Fig. 8 are replaced by a single crank 44 and a link 45 which oscillate a rocker member 46 to which the ends 42 and 43 of cable 14 are attached.

The milking member of my invention consists of a pumping member comprising two cylinders 47 and 48, a pair of teat attachment members 90 and 91, means for successively drawing the milk from two teats at a time into the pump, and means for discharging the milk into a suitable receptacle.

Cylinders 47 and 48 are nearly vertical and are held together by means of a ring clamp 49 and a base plate 50 supplied with hook members 51 and 52 adapted to seat in U-shaped members 53 and 54 screwed to post 26. The pump is prevented from being pulled off from its fastenings on post 26 by means of a latch 55, shown in Fig. 5 in full lines holding the pump in place and in dotted lines in Fig. 4 for allowing the pump to be removed. By this means said pump can be moved from one station to another and securely fastened at each station.

Cylinders 47 and 48 are supplied with pistons 56 and 57 comprising leather suction members 58 clamped between disks 59 and 60 screwed on the ends of piston rods 61. The lubrication of pistons 56 and 57 is procured by pouring water in the top of the cylinders 47 and 48, as shown in Figs. 4 and 5. Piston rods 61 are provided at their upper extremities with pieces 62 which project out at right angles from said rods and which are grooved at 63 to form heads 64.

In putting the pumps into operation pieces 62 are inserted into longitudinal grooves 65 in arms 22 and 23 of rocker member 21 near the center of said rocker member, where the travel of the arms 22 and 23 is least, and slid outward to drop into holes 66 passing completely through arms 22 and 23. Pieces 62 are kept in place by means of latches 67 having notches 68 which engage with the grooves 63 of said pieces and seat the same against heads 64. Means are hence provided for quickly and easily attaching and detaching the pump from the posts 26

and the piston rods from the rocker members 21.

The cylinder base plate 50 is provided with two openings 70 and 71 communicating with the interiors of the cylinders 47 and 48 and with a discharge chamber 72 formed by means of a funnel 73 having a milk outlet 74 and being removably attached to said base plate 50. Openings 70 and 71 are normally closed by means of a unitary valve 75 comprising valve flaps 75 and 76 pivoted in a pair of lugs 77 and 78 extending down from base plate 50. Lugs 77 and 78 meet at 79 to inclose a compression spring 80 which acts between projections 81 and 82 on valve flaps 75 and 76 and tends to normally keep said valve flaps seated, as shown in Fig. 4, said position of flap 76 being shown in dotted lines. When one of said flaps uncovers its opening said flap exerts a pressure 85 on spring 80 which communicates said pressure to the other flap, causing it to become quickly and positively seated. Each cylinder is provided with a pair of milk inlets 69 which communicate through stop cocks 83, 90 through ball check valves 84, through tubes 85, 86, 87 and 88 and by means of milk cups 89 of teat attachment members 90 and 91 with the cow's teats. The inlets 69 further communicate with release valves 92 held 95 seated by compression coil springs 93, the compression of which can be regulated by a thumb nut 94.

The operation of my milking machine is as follows. The cable 14 in its reciprocating motion oscillates all of the rocker members 26. Thus pistons 56 and 57, connected with one of said arms, are alternately raised and lowered in the cylinders 47 and 48. It will be noted that piston rods 61 cannot travel in line with the axis of the cylinders, but, due to the form of piston employed, this does not detract from the efficiency of operation. At the beginning of the up-stroke of piston 56 a vacuum will be created in cylinder 47 which opens the valves 84 on tubes 85 and 87 and seats valve flap 75. During the up-stroke milk is drawn from the cow's teats through the tubes 85 and 87 into the cylinder 47, the milk not reaching a height great enough to come in contact with the leather 58. When the direction of travel of piston 56 is reversed the valve flap 75 is opened, and valves 84 on tubes 85 and 87, and valve flap 76 are closed. During the down-stroke of piston 56 the milk in cylinder 47 is forced through opening 70, through discharge chamber 72, through discharge outlet 74 into any suitable receptacle 95. It will be noted that the same operations occur in cylinder 48 though they are alternate with those of cylinder 47. Hence the cylinders 47 and 48 produce alternate suctions in tubes 85, 87 and 86, 88, and produce continual discharge through outlet 74, milking pairs 130

of the cow's teats alternately, similar to the method employed in hand milking. The degree of vacuum desired can be regulated by the spring 93 and thumb nut 94 of the release valve 92, giving separate control over each pair of teats of each cow. This operation of the milking machine takes place until a cow or cows have been milked dry, whereupon the milking member is removed and set up at the next station. Figs. 1 and 2 show two sets of milking attachments 90 and 91 for milking two cows at once, thus expediting the process.

As can be clearly seen in the drawings, the milk at no time comes in contact with any leather or other substance tending to contaminate it, and the action causing the milk to be drawn from the cow's teats and discharged in a receptacle is made positive by use of the unitary valve and the use of both the suction and compression strokes of the pumps, which are quite essential to efficient milking machines.

An especially advantageous feature of my milking machine consists in the very short lengths of tubing through which the milk must travel and the accessibility of all parts subjected to the milk for cleaning purposes. The milking tubes may be inserted in hot water and with a very few strokes of the pump all parts subjected to the action of the milk can be readily cleaned, including the valves and the milking tubes. There are no stationary members subjected to milk travel and all parts of the apparatus may, after cleansing, be inserted in water to be kept in the best of condition for the next milking.

The release-valve mechanism in combination with the milking tubes makes it possible accurately to regulate the suction force applied through any tube in accordance with the requirements of the cow being milked, which is a matter of prime advantage in devices of this character.

45 I claim:

1. A milking apparatus comprising two parallel spaced members each extending entirely across the barn, means for simultaneously reciprocating both said members, a plurality of rocking arms each having operative connection with one or the other of said members, and a milking machine comprising a pair of upright cylinders with pistons in said cylinders and piston rods adapted to be connected for operation with any of said rocking arms.

2. A milking apparatus comprising a rotary member having a pair of oppositely-extended arms, a unitary cable attached at its ends to said arms, a series of pulley guides for causing said cable to extend in a pair of spaced parallel runs across the barn, means for rotating said member and arms to reciprocate the cable, a plurality of rocking arms each having operative connection with one

or the other of said arms, and a milking machine comprising a pair of upright cylinders with pistons in said cylinders and piston rods adapted to be connected for operation with any of said rocking arms.

3. A milking apparatus comprising a reciprocating member having a pair of spaced lugs thereon, a three-armed rocker member pivoted so that one of said arms extends between said lugs, a suction pump comprising a pair of upright pump cylinders each having a discharge opening, pistons in said cylinders, piston rods connecting said pistons with the ends of the two other rocker arms for simultaneously reciprocating said pistons in opposite directions, and valve mechanism beneath said openings for alternately opening and closing the pump cylinders.

4. A milking apparatus comprising a reciprocating member having a pair of spaced lugs thereon, a three-armed rocker member pivoted so that one of said arms extends between said lugs, a suction pump comprising a pair of upright pump cylinders each having a discharge opening, pistons in said cylinders, piston rods connecting said pistons with the ends of the two other rocker arms for simultaneously reciprocating said pistons in opposite directions, and a double valve yieldingly connected so that both parts move in unison for alternately opening and closing each cylinder.

5. A milking apparatus comprising a reciprocating member having a pair of spaced lugs thereon, a three-armed rocker member pivoted so that one of said arms extends between said lugs, a suction pump comprising a pair of upright pump cylinders each having a discharge opening, pistons in said cylinders, piston rods connecting said pistons with the ends of the two other rocker arms for simultaneously reciprocating said pistons in opposite directions, and a double valve yieldingly connected so that both parts move in unison for alternately opening and closing each cylinder; said valve being operated by the joint action of the compression and suction strokes of said pistons.

6. A milking machine comprising a pair of upright pump cylinders each having a discharge opening, pistons in said cylinders, means for simultaneously reciprocating said pistons in opposite directions, and a double valve yieldingly connected so that both parts move in unison for alternately opening and closing each cylinder.

7. A milking machine comprising a pair of upright pump cylinders each having a discharge opening, pistons in said cylinders, means for simultaneously reciprocating said pistons in opposite directions, and a double valve yieldingly connected so that both parts move in unison for alternately opening and closing each cylinder, said valve being operated by the joint action of the

compression and suction strokes of such pistons.

8. A milking machine comprising a pair of upright pump cylinders each having a discharge opening, pistons in said cylinders, means for simultaneously reciprocating said pistons in opposite directions, milking tubes connected with each of said cylinders, and a double valve yieldingly connected so that 10 both parts move approximately together for alternately opening and closing the discharge openings of the two cylinders.

9. A milking machine comprising a casing formed with a pair of inlet openings at 15 the top and a discharge opening at the bottom, a pair of upright pump cylinders connected with said casing and communicating therewith through said respective upper openings, pistons in said cylinders, means 20 for simultaneously reciprocating said pistons in opposite directions, milking tubes connected with each of said cylinders above the openings into the casing, and valve mechanism in said casing for alternately opening 25 and closing said inlet openings, said valves being simultaneously actuated by the forcing and suction action of the pistons in the respective cylinders.

10. A milking machine comprising a 30 chamber formed with a pair of inlet openings at the top and a discharge opening at the bottom, a pair of upright pump cylinders connected with said chamber and communicating therewith through said respective 35 upper openings, pistons in said cylinders, means for simultaneously reciprocating said pistons in opposite directions, milking tubes connected with each of said cylinders above the openings into the chamber, and a pair of flap valves in said chamber spring-held normally to close each of 40 said openings and actuated by the air forcing and suction action of the pistons in the respective cylinders alternately to open and 45 close communication with said cylinders.

11. A milking machine comprising a 50 chamber formed with a pair of inlet openings at the top and a discharge opening at the bottom, a pair of upright pump cylinders connected with said chamber and communicating therewith through said respective 55 upper openings, pistons in said cylinders, means for simultaneously reciprocating said pistons in opposite directions, milking tubes connected with each of said cylinders above the openings into the chamber, a pair of pivoted valves in the chamber each adapted to close one of said openings, and spring 60 means normally tending to hold said valves closed, actuation of said valves to effect properly timed opening and closing resulting from the air forcing and suction action of the pistons in the respective cylinders.

65 12. A milking machine comprising a

chamber formed with a pair of inlet openings at the top and a discharge opening at the bottom, a pair of upright pump cylinders connected with said chamber and communicating therewith through said respective upper openings, pistons in said cylinders, means for simultaneously reciprocating said pistons in opposite directions, milking tubes connected with each of said cylinders above the openings into the chamber, a 70 pair of pivoted valves in the chamber each adapted to close one of said openings, and a single spring engaging each of said valves and tending normally to hold both of them closed, opening of either of the valves increasing the effective force of the spring applied to the other valve to hold the same closed.

13. A milking machine comprising a chamber and a pair of upright cylinders 85 each connected and in communication therewith, pistons in said cylinders, means for simultaneously reciprocating said pistons in opposite directions, a pair of valves in said chamber each normally closing communication with one of said cylinders, and spring means within the chamber for holding said valves in said closing positions.

14. A milking machine comprising a 90 chamber formed with a pair of inlet openings at the top and a discharge opening at the bottom, a pair of upright pump cylinders connected with said chamber and communicating therewith through said respective upper openings, pistons in said cylinders, means for simultaneously reciprocating said pistons in opposite directions, milking tubes connected with each of said cylinders above the openings into the chamber, a 95 release valve in each of said milking tubes 100 for limiting the force of the suction stroke, and a valve mechanism in said chamber for alternately opening and closing communication therefrom to the cylinders.

15. A milking machine comprising a 110 chamber formed with a pair of inlet openings at the top and a discharge opening at the bottom, a pair of upright pump cylinders connected with said chamber and communicating therewith through said respective 115 upper openings, pistons in said cylinders, means for simultaneously reciprocating said pistons in opposite directions, milking tubes connected with each of said cylinders above the openings into the chamber, a 120 release valve in each of said milking tubes for limiting the force of the suction stroke, means for adjusting the effective force of said release valve, and valve mechanism in said chamber for alternately opening and closing communication therefrom to the respective pistons.

16. A milking machine comprising a 125 chamber formed with a pair of inlet openings at the top and a discharge opening at 130

the bottom, a pair of upright pump cylinders connected with said chamber and communicating therewith through said respective upper openings, pistons in said cylinders, means for simultaneously reciprocating said pistons in opposite directions, milking tubes connected with each of said cylinders above the openings into the chamber, a release valve in each of said milking tubes 10 for limiting the force of the suction stroke, a check valve in each of said milking tubes to permit movement of air and milk therethrough only in the direction of the cylinders and valve mechanism in said chamber 15 for alternately opening and closing communication therewith from each of the respective cylinders.

17. A milking machine comprising a chamber formed with a pair of inlet openings at the top and a discharge opening at the bottom, a pair of upright pump cylinders connected with said chamber and communicating therewith through said respective upper openings, pistons in said cylinders, means for simultaneously reciprocating said pistons in opposite directions, milking tubes connected with each of said cylinders above the openings into the chamber, a

check valve in each of said milking tubes for permitting flow of milk and air only in the direction to enter the cylinders, and valve mechanism in said chamber for alternately opening and closing communication therewith from each of the respective cylinders.

18. A milking apparatus comprising a constantly reciprocating member operative throughout a considerable extent within the barn, a plurality of rocker arms in several fixed positions within the barn, each operatively connected with and continuously rocked by said reciprocating member, a milking machine unit comprising a milk discharge and valve containing chamber, a pair of upright cylinders in communication therewith with pistons in said cylinders and piston rods adapted to be connected for operation with any of said rocking arms, and means for removably holding said milking machine unit in position to be operated from any one of said rocking arms.

In testimony whereof I affix my signature in presence of two witnesses.

KENNETH K. McLEOD.
